UNITED STATES PATENT OFFICE.

FRANKLIN W. KREMER, OF WADSWORTH, OHIO.

INJECTOR.

SPECIFICATION forming part of Letters Patent No. 299,229, dated May 27, 1884.

Application filed September 21, 1883. (Model.)

To all whom it may concern:

Be it known that I, FRANKLIN W. KREMER, a citizen of the United States, residing at Wadsworth, in the county of Medina and State of Ohio, have invented certain new and useful Improvements in Injectors, of which the following is a full, clear, and exact description.

This invention is in the nature of improvements in injectors for steam-boilers; and the object of the improvements is to specially adapt the injector covered by the United States Letters Patent No. 282,092, granted me July 31, 1883, for service on traction engines and locomotives.

15 The improvements consist in an injector convertible from a lifting-ejector to a lifting-injector, and from a lifting-injector to a non-lifting or forcing injector, in which the quantity of water fed is governable at will by means 20 of a single-movement lever controlling the steam-port and also the overflow; also, in a compound steam-valve operable by said lever for effecting such conversion in conjunction with the forcing and combining jets; also, in 25 the exhaust mechanism, and also in the overflow-controlling mechanism.

In the accompanying drawings, illustrating my invention, in the several figures of which like parts are similarly designated, Figure 1 30 is a view in front elevation. Fig. 2 is a vertical longitudinal section on the line xx ; Fig. 1, looking in the direction of the arrow, but with the lever turned to a point on its segment to open the steam-valve. Fig. 3 is a top 35 plan view; Fig. 4, a cross-section on the line yy ; Fig. 1; and Fig. 5, a side elevation, modified to show a separately-operated or non-automatic overflow.

The several sections a b c are fitted, preferably, with ground or packed or ground and packed joints, and secured together by clamp-bolts d d , engaging ears e e f f on the sections a and c , respectively, as in the patent referred to.

45 g is the steam-inlet in the section a , and h the water-inlet, also in said section, below and preferably on the side opposite the steam-inlet. The section a has a lifting-tube, i , communicating through port j with the steam-chamber k , and said tube and port are in a

diaphragm, l , extending across the section a , and dividing it transversely. Said diaphragm is also provided with a port, m , extended laterally outside as a pipe, and connected by a slip-joint coupling, n , with a pipe, o , extending laterally out and up from the section b to meet it. The lifting-tube p , provided with a base to fit in and close the counterbored end of section b , is interposed and held between sections a and b , and extends up near the lifting-tube i . The chamber q , formed between the diaphragm l and the base of tube p in the section a , is the suction-chamber. The upper face of the diaphragm l is fitted to receive a disk-like valve, r , overlying the ports j m , and having a port, s , to open one or both of said ports j m for the admission of steam to the injector, as will hereinafter appear.

t is a bonnet screwed into the head of section a , and adapted to receive the stem u of the valve r , said stem being separable from said valve, if desired. The stem is secured steam-tight in the bonnet by a collar, v , and stuffing-box v' . The valve is operated by a hand-lever, w , keyed to its stem, and said lever has a spring push-piece, a' , with a tooth, b' , to engage a segmental toothed or notched rack, c' , sprung from the bonnet t , to hold the valve positively in the desired positions. The opposite end of the lever w is provided with a cam, d' , to operate a lever, e' , which controls the overflow. This lever e' is pivoted by a yoke, f' , and screws g' g on the water-inlet, so as to move toward and from the injector, and its lower end enters a cavity, h' , in the overflow i' , where it operates upon the stem of the overflow check-valve j' . This overflow check-valve j' is seated in the inner end of the overflow-tube by pressure of water inside the injector to close the overflow and the said valve, and consequently the overflow is held open by the lever e' under the action of the cam d' of lever w . The outlet of the overflow surrounds the walls of cavity h' . The overflow-tube may be a part of or screwed into the section c . The valve j' is guided in its movement by its stem playing in a horizontal opening longitudinal of the cavity h' .

Between the sections b c is arranged the combining-tube k' , the base l' of which is fit-

ted between and separates the said sections. This base l' is provided with exhaust-holes m' , and said holes are closed by an annular float or automatic valve, n' , surrounding the tube k' , and having its internal diameter greater than the external diameter of said tube, so as to allow a passage between said tube and valve when the latter, as will presently appear, is seated on its lugs o' . The forcing-tube p' of the tube or pipe o centers in the tube k' .

The operation is as follows: When the parts are as shown in Fig. 3, the injector is closed or inoperative, or the valve r closed, and the upper end of the lever e' is thrown to its extreme outer position, while its lower end is at its corresponding inner position, to consequently throw and hold open the valve j' . If the push-piece a' be now pressed toward the lever w , its tooth or catch b' will be disengaged from the notched segment c' , when, if the lever w be turned till the notch 2 be engaged, the port s will register with port j to the lifting-tube and admit steam to the lifting-jet. This steam will create a vacuum in the suction-chamber, and will pass through the section b , which is the exhaust-chamber, through the holes $m' m'$ in the base of the combining-tube, forcing the annular valve n' on to its lugs o' , and escaping through the center opening of such valve out at the overflow. The overflow-check will not be seated by this pressure, because it is positively held open by the action of the cam d' on the lever e' . The vacuum or suction created by this steam will induce a flow of water, which takes the course of the steam through the tube p , and as soon as water appears at the overflow, thus giving notice of the establishment of a flow, the lever w is moved to the next notch, 3. By so turning the lever w the valve r has been rotated till its port s opens both ports j and m , thus admitting steam through the lifting-jet tube i , and also through the forcing-jet tube p' . At this point of adjustment of the lever w its cam d' is no longer in control of lever e' , and hence said lever is free to be moved, and the pressure of the steam and water against the overflow-check j' is sufficient to move said lever and close the overflow, and thus divert the whole column into the boiler. At the same time the pressure in the section c is sufficient to push the check n' to its seat or base l' and close the openings therein, so as to confine the outflow to the mixing or combining tube and prevent backflow. When it is desired to diminish the quantity of water injected, the lever is moved into one of the teeth 4 between the notch 3 and that end of the segmental rack, and such movement serves to operate the valve r to close the port j more or less, to admit more or less steam to the lifting-tube; and when the lever is at the extreme end of the teeth 4, or that end of the rack, the port j will be entirely closed, and the injector will work through its forcing-jet only. Thus it will be seen that when the lever w is at the first notch, 1, Figs.

1 and 3, the valve is so disposed that the machine is inactive, and when at 2 it acts as a lifter, discharging at the overflow; and when at 3 the steam is let into the forcing-jet also, 70 and, combining with the water, forces it through the combining or mixing tube into the boiler, both the lifting and forcing jets being active, and when at 4 the lifting-jet is shut off; but the machine continues to work 75 by force of the lifting-jet, but with a reduction in the quantity of water injected, because the forcing-jet has the double duty of lifting and forcing. To stop the machine, the lever w is brought back to the first notch, 1, thereby 80 closing the ports $j m$ and causing its cam to actuate the lever e' , and it in turn to open the overflow. The injector is thus in all its operative parts under the control of a single lever, and by said lever, as has been seen, may be 85 converted from a lifting-ejector into a lifting-injector, and from that to a non-lifting injector, with the water always under control as to quantity injected.

When the machine is used as a non-lifter, 90 the lever w is passed to the notch 4 immediately, and the check plate or valve o' , being automatic, is opened by the steam passing down, but closed as soon as the force begins to inject water.

Instead of a check-valve in the overflow, a rotary plug may be used, as indicated in Fig. 5, and the operation of such plug made independent of the lever, as shown, or by gearing therewith, dependent upon it.

In case of any derangement, access is readily had to the parts by means of the removable clamping-bolts.

What I claim is—

1. The combination, with the steam inlet 105 and valve, of an operating-lever provided with a spring push-piece and a toothed or notched segmental rack, with which said lever engages to govern the position of the valve, substantially as described.

2. The combination, with the steam-inlet, the valve therefor, an operating-lever provided with a spring-catch and a cam, and a toothed segment engaged by said spring-catch, of the overflow, a check-valve therein, and a 115 lever for said check-valve under the control of the cam of the steam-inlet-controlling valve-lever, substantially as and for the purpose described.

3. The combination, in an injector, of a 120 perforated or ported base or diaphragm for the combining or mixing tube; and an annular valve or plate automatically opening or closing such perforations or ports, substantially as shown and described.

4. The combination, with the overflow, of an automatically-seated check-valve, a lever to unseat or open the same, and the live-steam-valve-actuating lever operating in connection with said check-valve lever, substantially as 130 described.

5. The combination, with the steam inlets

and ports j m and the lifting and forcing tubes i and p' , respectively, of the steam-valve r , having the single opening s for ports j m , controlling such ports independently of one another, and operable with relation thereto to admit of the grading of the water-supply, and also the conversion of the machine from a lifting to a non-lifting injector, and vice versa, substantially as shown and described.

In testimony whereof I have hereunto set my hand this 17th day of September, A. D. 1883.

FRANKLIN W. KREMER.
